(57) **CLAIM**

The ornamental design for a lid with integrated nozzles for an air cooling device, as shown and described.

DESCRIPTION

FIG. 1 is a front, top, perspective view of a lid with integrated nozzles for an air cooling device; FIG. 2 is a rear, top, perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The broken lines illustrate portions of the lid with integrated nozzles for an air cooling device that form no part of the claimed design. The broken lines depicting an air cooling device depict environmental structure and bounds of the claimed design that form no part of the claimed design.
